ASH RECEPTACLE

John Visser, Grand Rapids, Mich., assignor, by
mesne assignments, to Reconstruction Finance
Corporation, Detroit, Mich., a corporation of the
United States

Application January 18, 1937, Serial No. 121,164

2 Claims. (Cl. 206—19.5)

This invention relates to a pivotal type of ash receptacle, and more particularly to a spherical type receptacle having a detachable ash container adapted to be swung into exposed and concealed positions.

An object of this invention is to provide a receptacle having a container adapted to be swung into exposed and concealed positions with a novel connection for holding the container in place in the receptacle.

Another object of this invention is to provide a receptacle of the aforementioned type which can be economically manufactured on a large production basis from standard metallic sheets.

In accordance with the general features of this invention, there is provided a receptacle including a housing, a container support in said housing, and a container detachably connected to said support by a rotary resilient snap-on connection comprising clip means engaged by a relative rotary movement of the support and container, the support being connected by a pintle to the housing, whereby said container may be swung out of said housing into an exposed and accessible position.

Another feature of the invention relates to the use of the pintle pin extending between the container support and housing to serve as a part of the connection between the detachable container and the support.

Other objects and features of this invention will more fully appear from the following detailed description, taken in connection with the accompanying drawings, in which:

Figure 1 is a front view of a spherical receptacle embodying the features of this invention and illustrating it as being mounted upon a panel such as the dashboard of an automotive vehicle;

Figure 2 is a vertical cross-sectional view taken on the line II—II of Figure 1, looking in the direction indicated by the arrows, and showing the ash container in its closed or concealed position;

Figure 3 is a cross-sectional view taken on the line III—III of Figure 1, looking downwardly, and also showing the ash container in closed or concealed position;

Figure 4 is a side elevational view partly in section of the ash receptacle, showing the receptacle applied to a panel, and illustrating the container in its open or exposed position;

Figure 5 is a side view of the ash receptacle showing the container swung a quarter of a turn about the pintle into the housing, so that the container is disposed in a position halfway between its open and closed positions;

Figure 6 is a plan view of the receptacle shown in Figure 5, with the container in its aforesaid intermediate position;

Figure 7 is a bottom view of the ash receptacle as shown in Figure 6 and illustrating the stop means for limiting the movement of the container at its open and closed positions, and also illustrating in dotted lines the progressive movement of the container toward an open position;

Figure 8 is a fragmentary view of the bottom of the ash receptacle showing the position of the abutment or stop means when the container is in its fully open position;

Figure 9 is a sectional or explosion view of the elements which comprise my spherical type ash receptacle, and illustrating in dotted lines the location of the pintle pin with reference to certain of the elements; and

Figure 10 is a detail view of the novel snap-on clip means of my receptacle for detachably connecting the container to the pintle pin carried by the housing and showing the pintle pin in dotted lines in the drawings.

In the drawings:

The reference character 10 designates generally a mounting panel such, for example, as the dashboard of an automobile, which is provided with a circular opening 11 of such diameter as to receive and accommodate the outer shell or housing 12 of my novel hemispherical ash receptacle. This housing 12 may be secured in any suitable manner to the mounting panel 10, as for example by means of lateral pins 30 or tangs 13 punched from the body of the housing and suitably secured to projections 13a or other means on the panel, as shown in Figure 3. Inasmuch as my present invention is not concerned with the details of the means employed for fastening the shell or housing of my receptacle to the panel, such details have not been illustrated in full. It is obvious, however, that any suitable fastening means may be used for this purpose.

The housing 12 has suitably anchored to it in a vertical position a pintle pin 14, about which the ash container 15 is adapted to be swung from the closed position shown in Figure 2 to the open position shown in Figure 4. The container 15, as shown in detail in Figure 9, has secured in it a back plate 16 which is flanged and suitably secured, as by welding, to the marginal or band portion 18 of the container. This marginal or band portion 18 of the container is notched at 50 opposite sides as at 18a (Figure 3) to an extent not only sufficient to permit the ends of the pintle pin 14 to extend therethrough, but also to enable a limited amount of relative rotary movement between the container 15 and the pin 55 necessary to disengage from the pin the free ends of the oppositely facing resilient arms of the clip device 17 shown in Figure 10. This clip device, while provided with free and resilient oppositely facing clips or arms, is secured between the 60

arms by means of welds or the like 17a to the back plate 16 (Figures 9 and 10). It will be evident that by rotating the container 15, which carries this clip device 17, in a counter-clockwise direction, it is possible to disengage the clip means from the pin 14, and that by rotating the container 15 in a clockwise direction, it is possible to engage the arms of the clip device 17 with the pin 14. Thus, there is provided a simple 10 rotary resilient snap-on connection for enabling ready application of the container to the pintle pin 14.

The container 15, as will be readily perceived from Figure 9, is cut away as indicated at 20 so 15 as to enable ashes or the like to be disposed in the container. Also, the container 15 is provided with a match-striking surface 20a.

The band or marginal portion 18 of the container 15 is adapted to telescope the circular or 20 band portion 19 of a face plate 21. This band portion 19, unlike the band portion 18, is not provided with diametrically opposite notches 18a, as shown in Figure 3. The outer surface of the face plate 21 may be suitably ornamented, as by 25 providing it with a grain finish or the like.

Now, it should be noted that while the band portion 19 of the face plate 21 is not provided with notches such as the notches 18a, it is provided with circular holes through which the ends 30 of the pintle pin 14 extend, as will be evident from Figures 2 and 4. This face plate, together with the container when the latter is disposed in telescoping relationship with the face plate, is adapted to be rotated about the fixed pintle pin 35 14. However, it is not removable from the pin, as is the case with the container 15, which is merely snapped into retained engagement with the pintle pin by means of the clip device 17, previously described.

40 The face plate 21, on the bottom of its band portion 19, is provided with a pair of spaced studs 27 and 28, both of which are freely movable within a widened portion 22 of an arcuate slot formed in the bottom of the shell or housing 12. It is 45 only while the container is in an intermediate position with reference to its open and closed positions that the studs 27 and 28 are movable in the widened portion 22 of this slot. The stud 28 is movable in the narrowed portions 23 and 24 50 of the slot during rotation of the container from open to closed position. It serves as a stop, as is evident from Figures 7 and 8. The stud 27, however, rides under the under surface of the shell opposite the narrow portions 23 and 24 of the 55 slot, and snaps into either of the widened ends 25 and 26 thereof in the opposite rotations of the container to retain the ash receiving container in either open or closed position, depending upon which direction the container is rotated. Thus, 60 it will be appreciated that the stop 28 serves as a guiding stop, whereas the stop 27 serves as a frictional means for retaining the ash receptacle in either open or closed position, depending upon which direction the ash receptacle is rotated with 65 respect to the pintle or pivot pin 14.

It should also be noted that the portions of the wall of the housing or shell 12 (Figures 7 and 8) projecting between the widened portion 22 of the slot and the widened end portions 25 and 26 of the 70 slot are necessarily possessed of some resiliency, so as to permit of the end of the projection

27 on the face plate 21 passing thereunder. Hence, it follows that after the stud 27 passes from under these resilient portions of the wall of the housing, it engages side edges of the slot to aid in the retention of the ash receptacle in 5 the position to which it is swung.

From the foregoing, it will be apparent that I have provided a receptacle wherein the container for receiving ashes may be readily swung and retained in either exposed or concealed position 10 with respect to the housing of the receptacle, and that when it is necessary to empty the ash receptacle it may be quickly and easily disengaged and removed from the face plate 21 which it normally telescopes. When it is in telescoping relationship with the face plate, as shown in Figure 2, it will be perceived that there is a space 18b between the back of the receptacle and the ornamented portion of the face plate. This is desirable, since it precludes any of the hot contents, 15 such as ashes, of the receptacle from marring the finish of the plate 21.

All of the parts of my novel ash receptacle, with the possible exception of the pintle or pivot pin 14, may be economically manufactured on a 25 large production basis from a standard gauge of sheet material, such as steel sheets. Moreover, the ash receptacle is readily applicable to a mounting panel such as the dashboard of an automobile, without requiring any extensive changes 30 in the panel aside from the aperturing of the panel to accommodate the ash receptacle and the provision of a suitable means for anchoring the receptacle to the panel.

I am aware that many changes may be made 35 and numerous details of construction may be varied through a wide range without departing from the principles of this invention, and I, therefore, do not purpose limiting the patent granted hereon otherwise than necessitated by the prior 40 art.

I claim as my invention:

1. In combination with a supporting plate having an opening therethrough, an ash receiver shell extending bodily through said opening and attached to said plate, means including a pin extending diametrically of said shell on the open side thereof, and an ash container pivoted to said shell on said pin for rotation into and out of said shell and detachably supported directly on said pin by a rotary resilient snap-on connection, said connection comprising a resilient clip on a side wall of said container and movable into retaining engagement with said pin upon rotary movement of the container transversely of the axis of said 55 pin.

2. In combination with a supporting plate having an opening therethrough, an ash receiver shell extending bodily through said opening and attached to said plate, means including a pin extending diametrically of said shell on the open side thereof, and an ash container pivoted to said shell by said pin for rotation into and out of said shell and detachably supported directly on said pin by a resilient snap-on connection, said connection comprising a resilient clip on a side wall of said container and movable into retaining engagement with said pin upon movement of the container transversely of the axis of said pin.
